Specification for Design.

Patented Aug. 2, 1921.

Application filed April 29, 1921. Serial No. 465,539. Term of patent 3½ years.

To all whom it may concern:

Be it known that I, ELI E. LAROCQUE, a citizen of the United States, residing at Pawtucket, in the county of Providence and State of Rhode Island, have invented a new, original, and ornamental Design for Time-Indicators for Use in Laundries, of which the following is a specification, reference be-

ing had to the accompanying drawing, forming a part thereof.

The figure is a perspective view of the timing device embodying my design.

I claim:

The ornamental design for a time-indicator for use in laundries, as shown.

ELI E. LAROCQUE.
